DESIGN FOR A HOBBYHORSE

Sterling Ward, St. Joseph, Mo.

Application June 24, 1936, Serial No. 63,454

Term of patent 14 years

To all whom it may concern:

Be it known that I, Sterling Ward, a citizen of the United States, residing at St. Joseph, in the county of Buchanan and State of Missouri, have invented a new, original, and ornamental Design for a Hobbyhorse, of which the following is a specification, reference being had to the accompanying drawing, forming a part thereof.

Figure 1 is a side elevation of a hobbyhorse, showing my new design.

Fig. 2 is a plan view of the hobbyhorse.

Fig. 3 is a front end elevation of the same, and, Fig. 4 is a rear end elevation of the hobbyhorse.

I claim:

The ornamental design for a hobbyhorse, as shown.

STERLING WARD.
